DOUBLE ROTOR JET SWITCH

Jerome W. Gootherds, Redwood City, Calif., assignor to American Radiator & Standard Sanitary Corporation, New York, N.Y., a corporation of Delaware

Application June 23, 1958, Serial No. 743,553

6 Claims. (Cl. 200—32)

This invention relates to and in general has for its object the provision of an all-position mercury jet switch and constitutes an improvement to the all-position jet switch disclosed in the Gootherds Patent No. 2,791,650, dated May 7, 1957, "All-Position Rotary Jet Switch."

Switches of this character are designed for transmitting signals from a fast moving object, such as an airplane or missile, to the ground. Since a missile can be subjected to an acceleration field equivalent to, say 100 G's, any switch of the character under discussion carried by a missile must operate without any appreciable effect from such an acceleration field.

The switch disclosed in the Gootherds Patent No. 2,791,650 is made to operate independently of acceleration fields by rotating its single rotor at such a speed that the centrifugal force developed is so high as compared with any acceleration field to which the switch may be subjected, that the latter is negligible for all practical purposes. However, the speed of the rotor of the Gootherds switch determines the number of times that each of the switch circuits is closed per minute, and for many purposes and reasons this is a speed too high for effectively receiving and/or recording the transmitted impulses.

More specifically, one of the objects of this invention is the provision of a rotary jet switch including a stator provided with a ring of contact pins; a first rotor arranged to rotate at a speed sufficient to make negligible any acceleration field to which the switch may be subjected, and provided with an annular chamber arranged to receive a body of mercury or other suitable liquid conductor; a second concentric rotor arranged to rotate at a lower speed than said first rotor and provided with a nozzle orifice in alignment with said contact pins; and means for delivering mercury from said body of mercury to said orifice, and whereby the speed of the second rotor determines the rate at which each circuit of the switch is closed.

A further object of this invention is the provision of a switch of the character above described wherein mercury from the body of mercury carried by the first rotor is delivered to the orifice of the second rotor communicating at one end with said orifice and having its other open end heading into the annular body of mercury carried by the first rotor.

Still another object of this invention is the provision of a rotary jet switch of the character above described which can be readily assembled and disassembled.

The invention possesses other advantageous features, some of which, with the foregoing, will be set forth at length in the following description where those forms of the invention which have been selected for illustration in the drawings accompanying and forming a part of the present specification, are outlined in full. In said drawings, one form of the invention is shown, but it is to be understood that it is not limited to such form,

2

since the invention as set forth in the claims may be embodied in other forms.

Referring to the drawings,

Fig. 1 is a vertical mid-section of a rotary mercury jet switch embodying the objects of my invention.

Fig. 2 is a horizontal section taken on the section line 2—2 of Fig. 1.

The switch as illustrated in these various figures includes a cylindrical base 1 provided with a lower flange 2 for attachment to an electric motor, and with an upper depressed flange 3 formed with an upstanding shoulder 4.

Seated on the flange 3 in interlocking engagement with the shoulder 4 is the annular base 5 of a plastic bearing supporting member 6, the base 5 being provided with an annular flange 7. Fixed to the upper end of the member 6 is a collar 8, and secured thereto is a peripherally channeled bearing sleeve 9. Aiding in securing the sleeve 9 to the collar 8 is a retaining ring 11 seated in one of the peripheral channels 12 of the bearing sleeve.

Formed integral with the upper end of the bearing sleeve 9 is a radially extending hub 13 provided on its periphery with an upstanding skirt 14.

Molded around the upper end of the collar 8 is a plastic connector plug or ring 15, the outer upper edge of the collar being upset to aid in holding the plug in place. Formed in the plug 15 is a ring of equally spaced vertical bores 16, each merging at its lower end with a radially extending channel 17. Fixed within each of the vertical bores 16 is a metal connector sleeve 18. Extending into each of the radial channels 17 is a terminal 19 secured at its inner end to its associated connector sleeve 18 and provided at its outer end with an eyelet 21. The eyelets 21 serve as the positive terminals of the switch and are arranged to be connected with a suitable harness.

Formed in the upper end of the bearing supporting member 6 is a radial bore 22, and extending therethrough is an electric lead 23 electrically connected at its inner end with the collar 8, the lead 23 serving as the negative terminal of the switch.

Mounted within the bearing sleeve 9 and secured thereto is an outer ball bearing race 24 cooperating with a mating inner ball bearing race 25 and intervening ball bearings 26. Mounted in the inner race 25 is a shaft 27 arranged, as will presently be more fully described, to be coupled with an electric motor mounted on the flange 2 of the base 1.

Disposed beneath the bearing races 24 and 25 is a bearing spacer 28, and secured to and within the bearing sleeve 9 beneath the bearing spacer 28 is a bowed retaining ring 29. Threaded to the shaft 27 in abutment with the race 25 is a nut 31 provided at its lower end with wrench sockets 32.

As a result of this construction, the collar 8 and plug 15 can be readily removed from the rest of the assembly by merely removing the retaining ring 11. And the bearing retaining sleeve 9, races 24 and 25, and bearing spacer 28 can be removed from the shaft by simply backing off the nut 31 and removing the bowed retaining ring 29.

Molded on the bearing retaining sleeve 9 immediately above the plug 15 is a second annular plastic ring or plug 33, and mounted therein is a ring of depending metal contact prongs 34 each adapted to be snugly received in one of the contact sleeves 18 so as to be placed in electrical communication with one of the positive terminals 19.

Molded in the plug 33 and affixed to the upper end of each of the prongs 34 is a radially extending metal

pin 35 protruding well beyond the periphery of the plug 33.

Seated on the flange 7 of the bearing supporting member 6, and detachably secured thereto by machine screws 41 is an upstanding cylindrical steel shell or casing 42 provided with radial flanges 43 and 44 at its lower and upper ends, respectively. Surrounding and straddling the base flange 3 and the casing flange 43 is an annular split clamp 45 serving to detachably lock the base 1, member 6, and casing 42 together into a rigid structure.

Seated on the casing top flange 44 is the flange 46 of a plastic (dielectric) ring or collar 47, the body of said ring being snugly accommodated within the upper end of the casing 42 and detachably secured thereto by machine screws 48. Here it should be noted that although the collar 47 has been illustrated and described as being made of a dielectric material, this is immaterial to the operation of the device in so far as its electrical circuit is concerned. Seated on the flange 46 is a dished cover or cap 49 provided with a peripheral flange 51, and surrounding the flanges 44 and 51 is a locking channel 51a. Surrounding the channel 51a is a split ring clamp 52 for detachably holding the channel 51a in locking engagement with the flanges 44 and 51.

Snugly accommodated within the plastic ring 47 is a bearing retaining sleeve 53, the sleeve 53 and the ring 47 being cemented together by two annular rings 54 of a resin accommodated in channels 55. Locking the ring 47 to the sleeve 53 is a machine screw 56 recessed within the ring 47. Accommodated within the sleeve 53 is an outer ball race 57 cooperatively associated with an inner ball race 58 and intervening ball bearings 59. Secured to the top of the sleeve 53 by screws 61 is a cap 62 provided with an internal ring gear 63 formed in a central depressed annular hub 64. Formed on the lower face of the cap 62 is an intermediate annular channel 65.

The entire structure so far described, with the exception of the inner ball races 57 and 58 and the shaft 27, is stationary and rigid and for ready reference can be considered as the frame or stator of the switch.

Journaled on the shaft 27 through ball bearing assemblies 71 and 72 disposed between a spacing sleeve 73 is a first rotor generally designated by the reference numeral 74 and including a bearing sleeve 75 and an upstanding annular ring 76. Mounted on the ring 76 is an internal ring gear 77 here shown as being of a diameter slightly smaller than the diameter of the internal ring gear 63. Seated over the ring 76 and secured thereto by screws 78 is the inwardly extending annular flange of a depending collar or skirt 79 circumscribing the stationary skirt 14 with positive clearance. Here it should be noted that the peripheral face of the ring 76 also has positive clearance with the skirt 14.

Circumscribing the lower end of the skirt 79, and recessed therein, is a pair of identical semicircular ring sections 81 and 82, each provided at one of its ends with a boss 83 and each provided at its other end with a shoulder 84. Formed in each adjacent pair of bosses 83 and shoulders 84 are aligned bores 85 and 86, respectively. Each bore 85 is stepped and threaded over its enlarged portion, and each of the bores 86 is large enough to clear the body of the machine screw 91. Disposed between the abutting faces of each pair of bosses 83 and shoulders 84 is a gasket 87, and extending partially through each bore 85 is a nipple 88 formed with an enlarged head 89. Nipples 88 are held in bores 85 by pressed fits. Threaded into the end of each bore 85 is a machine screw 91 serving to lock the two rings 81 and 82 tightly about the skirt 79 and to plug the end of bore 85.

Connected to the head 89 of each of the nipples 88 is a scoop tube 92 having its outer end contoured so as to lie on a circle concentric to the axis of the switch.

Here it should be noted that, as indicated in Fig. 2, the rotor 74 is assumed to rotate in a clockwise direction.

Extending through the lower face of the left hand boss 83 and through the lower side of the nipple 88 is a stepped circular hole 93, and seated therein is a disc 94 provided with a small jet orifice 95 in vertical alignment with the contact pins 35. The right hand boss 83 is similarly provided with a circular disc 96 having a central orifice 97, but here the orifice is directed inwardly in radial alignment with a port or opening 98 in the skirt 79 so that any mercury passing through the orifice 97 will impinge on the stationary skirt 14. From Fig. 1 it will be noted that the skirt 14 is in electrical communication with the negative lead 23.

Fixed to the shaft 27 is a second rotor generally designated by the reference numeral 101, including a central spider 102 serving among other things to support the bearing race 58.

Secured to the spider 102 by screws 103 is an inverted rotor casing 104 contoured to circumscribe the skirt 79, formed with an inverted mercury sump 105 and provided with a depending peripheral skirt 106. Mounted within the skirt 106 and sealed thereto by an O ring 107 is an annular ring 108 provided with an inner flange 109 circumscribing the stationary plastic plug 33 with positive clearance. As shown in Fig. 1, the ring 108 is contoured so as to provide a mercury sump 111 generally opposing the sump 105 and in vertical alignment with the ring of contact pins 35.

Overlying the lower face of the annular ring 108 is a retaining snap ring 112 accommodated in a channel 113 formed in the inner face of the skirt 106. As a result of this construction, it will be seen that the casing 104 and its associated ring 108 form an annular channel or chamber 114 which in cross-section converges outwardly. Therefore, during the rotation of the rotor 101 and as a result of the centrifugal force developed, any mercury contained in the channel 114 will move outwardly and be held in engagement with the inner surface of the skirt 106. Here it should be noted that the outer ends of the scoop tubes 92 are positioned immediately adjacent the skirt 106 and therefore in the locus of any annular body of mercury traveling with the skirt 106. If then the mercury is traveling at a speed sufficiently greater than the scoop tube, mercury will travel inwardly through the scoop tubes and will be ejected through the orifice 95 into engagement with the contact pins 35. After the mercury jet successively contacts the pins 35, the mercury drops into the lower part of the channel or chamber 114 and climbs the walls thereof to join the annular body of mercury located on the constricted portion of the channel. Each time that the mercury jet hits one of the contact pins 35, the electrical circuit is completed through one of the positive terminals 19.

The drive for the rotor 101 includes a shaft 121 journaled in the spider 102 through a pair of ball bearing units 122 and 123 held in spaced relationship by a spacing sleeve 124. Provided on the lower end of the shaft 121 is a pinion 125 arranged to mesh with the internal gear 77 affixed to the first rotor 74. Fixed to the upper end of the shaft 121 by a pin 126 is a pinion 127 in mesh with the stationary internal ring gear 63. As a result of this construction, the rotation of the spider 102 with the shaft 27 causes the shaft 121 to rotate bodily about the axis of the shaft 27. Since the ring gear 63 is fixed against rotation, the bodily rotation of the pinion 127 about the axis of the shaft 27 will cause the shaft 121 to rotate about its own axis. The resulting rotation of the pinion 125 will then cause the ring gear 77 to rotate and with it the first rotor 74. This structure therefore constitutes a planetary gear system whereby the rotation of the shaft 27 will cause the two rotors 74 and 101 to rotate at a differential speed, but both in the same direction, clockwise as herein illustrated.

Formed on the lower end of the shaft 27 is a wrench face 131, and secured thereto by a set screw 132 is a coupling generally designated by the reference numeral 133. The coupling 133 includes an upper collar 134 mounting the set screw and a bushing 135 for receiving the lower end of the shaft 27. Bonded to the lower end of the collar 134 is a dielectric disc 136, and bonded to the lower face of the disc 136 is a lower collar 137 formed with a central bore 138 for the reception of a motor shaft 139. Threaded in the collar 137 is a set screw 141 arranged to engage a wrench face 142 formed in the end of the motor shaft 139.

Now assuming that the sump 111 of the second or outer rotor 101 has been supplied with a suitable quantity of mercury. When the switch is placed in operation the mercury is thrown to the outer periphery of the annular channel or chamber 114 and held there as an annular ring 145 against any acceleration field of lower magnitude than the centripetal acceleration generated by the rotation of the annular chamber 114. To perform the switching function of the switch, the first rotor 74 must rotate at a speed less than the speed of the rotor 101. Here it should be recalled that the mouth of each scoop or pitot tube 92 is elevated within the annular ring 145 of mercury. A stagnation pressure is developed at the mouth of each tube proportional to the square of the difference in the speeds of the second and first rotors 101 and 74. If the speed ratio of these rotors is 2 to 1 or greater, sufficient stagnation pressure will exist at the entrance of the tube to overcome the pressure due to the centrifugal force on the column of mercury in the tube, all the way to the center of rotation. Thus pressure exists behind the orifice 95 to force a jet of mercury through the orifice to sequentially contact the pin 35 of the stator. The scoop tube 92 on the right hand side of the switch, as illustrated in Fig. 2, as previously explained, picks up mercury in the same way as its diametrically opposed counterpart, but the mercury jet passing through its associated orifice 97 continuously impinges on the annular skirt 14 so as to complete the electrical circuit.

The nipple 88 is made of metal as shown on the drawing (Fig. 2), although this is immaterial.

The ring sections 81 and 82 are only in casual electrical communication with the negative lead 23 through ball bearings and gear meshes. This cannot be considered an uninterrupted low-resistance path. A closed circuit through one pin will be traced—start with eyelet 21, up terminal 19, through connecting sleeve 18, contact prong 34, metal pin 35. Then contact is made by a mercury jet being forced through orifice 95. The circuit continues through the mercury down scoop tube 92 (left side of Fig. 2) annular ring of mercury 145, up the mercury in scoop tube 92 (right side of Fig. 2), to the orifice 97. The mercury jet passing through orifice 97 impinges on annular skirt 14 which is in electrical communication with the negative lead 23. This completes the circuit from eyelet 21 to negative lead 23 when the mercury jet from orifice 95 is impinging on any particular pin 35. All other pins 35 are open-circuited with respect to the negative lead 23.

By resorting to this construction, not only is the circuit completed, but also the rotor 74 is in substantially dynamic balance.

Further, the entire structure has been so designed that it can be readily assembled and disassembled.

Although there is nothing critical concerning the dimensions of the switch, it has been found that the switch may be effectively made with from 60 to 90 equally spaced contact pins 35; that the shaft 27 and its rotor 101 may be driven at a speed in the order of 3600 r.p.m.; and that the gear ratios of the planetary gears may be such as to drive the rotor 74 at a speed in the order of 1200 r.p.m. This of course produces a speed ratio of 3 to 1 between the outer rotor 101 and the inner rotor 74, this ratio

being ample to produce the stagnation pressure required to force mercury inwardly through the scoop tubes 92. The speeds of both the outer and inner rotors is also sufficient to make any acceleration field to which the device may be subjected negligible for all practical purposes, and consequently, the switch will operate effectively in any position.

The use of mercury has been called for merely as illustrative of a good fluid conductor. Other fluid conductors can of course be used.

I claim:

1. A rotary jet switch comprising: a stator provided with a circle of insulated contact pins; a first rotor circumscribing said stator adjacent said circle of contact pins and having an orifice directed towards said circle of contact pins; a second rotor provided with an annular chamber circumscribing and encompassing said circle of contact pins and said first rotor; means for rotating said first and second rotors at different speeds and in the same direction; and a conduit fixed at one end to said first rotor in communication with said orifice, the other end of said conduit being located adjacent the periphery of said chamber and facing in a direction opposite to the direction of rotation of said rotors.

2. A rotary jet switch comprising: a stator provided with a circle of insulated contact pins; a first rotor concentric with said circle of contact pins and provided with an orifice directed towards said circle of contact pins; a second rotor coaxial with said circle of contact pins and provided with an annular chamber encompassing said contact pins; means for rotating said first and second rotors in the same direction; and a conduit fixed at one of its ends to said second rotor in communication with said orifice and having its other end located adjacent the periphery of said annular chamber and facing in a direction opposite to the direction of rotation of said rotors.

3. A rotary jet switch comprising: a stator; a drive shaft journaled in said stator; a circle of insulated contact pins mounted on said stator coaxially with said drive shaft; a first rotor journaled on said shaft and provided with an orifice directed towards said circle of contact pins; a second rotor fixed to said drive shaft coaxially therewith and provided with an annular chamber encompassing said contact pins and said orifice; means for driving said first and second rotors at different speeds but in the same direction; and a conduit fixed at one end to said first rotor in communication with said orifice, the other end of said conduit being located adjacent the periphery of said chamber and facing in a direction opposite to the direction of rotation of said chamber.

4. A rotary jet switch comprising: a stator; a drive shaft journaled in said stator; a circle of insulated contact pins mounted on said stator coaxially with said shaft; a first rotor journaled on said shaft and provided with first and second diametrically opposed orifices, one of said orifices being directed to said circle of contact pins and the other of said orifices being directed towards said stator; a second rotor fixed to said drive shaft coaxially therewith and provided with an annular chamber encompassing said contact pins and said orifice; means for driving said rotors at different speeds but in the same direction; and first and second diametrically opposed conduits each fixed at one end to said first rotor in communication with one of said orifices, the other end of each conduit being located adjacent the periphery of said chamber and facing in a direction opposite to the direction of rotation of said rotors.

5. A rotary jet switch comprising: a stator including upper and lower stacked insulating rings; a circle of equally spaced contact pins mounted in said upper ring; a circle of equally spaced electric terminals mounted in said lower ring, there being one such terminal for each of said contact pins; quickly detachable means for electrically coupling said terminals to said contact pins in

response to the movement of said lower ring towards said upper ring; a first rotor circumscribing said stator adjacent said circle of contact pins and having an orifice directed towards said circle of contact pins; a second rotor provided with an annular chamber circumscribing and encompassing said circle of contact pins and said first rotor; means for rotating said first and second rotors at different speeds and in the same direction; and a conduit fixed at one end to said first rotor in communication with said orifice, the other end of said conduit being located adjacent the periphery of said chamber and facing in a direction opposite to the direction of rotation of said rotors.

6. A rotary jet switch comprising: a stator provided with a circle of insulated, equally spaced contact pins; a shaft journaled in said stator coaxially with said circle of contact pins; a first rotor journaled on said shaft and provided with an orifice aligned with said circle of contact pins; a second rotor fixed to said shaft for rotation

10
5

15

therewith and provided with an annular chamber circumscribing and encompassing said circle of pins and said first rotor; a first internal ring gear provided in said stator coaxial with said shaft; a second internal ring gear provided in said first rotor coaxial with said shaft; a stub shaft journaled in said second rotor eccentric to said shaft; a first pinion fixed to said stub shaft in mesh with said first ring gear; a second pinion fixed to said stub shaft in mesh with said second ring gear; and a conduit fixed at one end to said first rotor in communication with said orifice, the other end of said conduit being located adjacent the periphery of said chamber.
